UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

CAR-TRUCK.

1,371,586.

Specification of Letters Patent. Patented Mar. 15, 1921.

Application filed July 25, 1919. Serial No. 313,287.

To all whom it may concern:

Be it known that I, CHARLES T. WESTLAKE, a citizen of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification.

My invention relates to railway car trucks, the principal objects of my invention being to generally improve upon and simplify the construction of the existing forms of trucks of the type to which my invention relates; to provide a construction which materially increases the flexibility of the truck; and to provide means for distributing the load of the car on the journals.

With the foregoing and other objects in view, my invention consists in certain novel features of construction and arrangement of parts, hereinafter more fully described and claimed, and illustrated in the accompanying drawings, in which—

Figure 1 is a plan view of a car truck of my improved construction, a portion of one of the side frames thereof being shown in horizontal section.

Fig. 2 is a side elevational view of my improved car truck.

Fig. 3 is a cross section taken approximately on the line 3—3 of Fig. 1.

Fig. 4 is an enlarged vertical section taken approximately on the line 4—4 of Fig. 3.

Fig. 5 is a detail section taken approximately on the line 5—5 of Fig. 3.

Fig. 6 is an enlarged elevational view of one of the rockers utilized on my improved truck.

Referring by numerals to the accompanying drawings, which illustrate a practical embodiment of my invention, 10 designates the side frames of my improved truck, said frames being preferably cast and provided in their end portions with vertically disposed openings 11 in which are arranged for vertical movement, journal boxes 12, and 50 the latter serving as bearings for the ends of wheel carrying axles 13.

Formed integral with the end portions of the side frames immediately above the openings 12 are housings 14 which are occupied by the upper portions of coil springs 15, the

lower ends of which rest upon the tops of the journal boxes 12.

The central portion of each side frame 10 is formed with a vertically disposed box-like structure 16, the side walls of which 60 are provided with openings 17 and formed in said structure below said openings is a substantially cup-shaped seat or socket 18.

The pair of side frames of each truck are connected by a relatively light transverse 65 member or bolster 19, the ends of which are provided with integrally formed substantially spherical heads 20 which bear directly upon the sockets 18.

Formed integral with the sides of the end 70 portions of this bolster 19 and with the sides of the heads 20 are outwardly projecting pairs of ears or lugs 21 which occupy positions immediately adjacent the inner side walls of the box-shape structures 16, and 75 thus when the bolster and side frames are properly assembled, they are interlocked by means of said pairs of lugs or ears. However, there is sufficient play between the inner faces of the pairs of lugs or ears 21 and 80 the adjacent faces of the inner walls of the structures 16 to permit the side frames to rock freely in all directions for a limited distance, such result being accomplished by virtue of the ball and socket connections between the end of the bolster and the side 85 frames, and as a result, the truck frame has a relatively high degree of flexibility.

Formed at the center of the bolster 19 is a pocket 22 which is occupied by a compression spring 23 and supported by the latter is the central portion of a body bolster 24. Extending downwardly through the bottom of this body bolster through the spring 23 and through the bottom of pocket 22 is a 95 king pin 25, the same serving as an axis for the turning movement of one bolster relative to the other, and as said king pin is provided in its lower end with a key or cotter pin 26, it serves to tie the two bolsters 100 together.

Fixed in any suitable manner to the undersides of the end portions of the body bolster 24 are brackets or bearings 27, and pivotally connected thereto by means of 105 pins or bolts 28 are rockers 29, the under-surfaces of which latter bear directly on top of flat bearing faces 30 which are formed on top of the central portions of the side frames 10. There is preferably a pair of these 110

herein shown and described, without departing from the spirit of my invention, the scope of which is set forth in the appended claims.

I claim:

1. In a car truck, a pair of spring supported side frames, a bolster pivotally connecting the same, and a car body supporting spring carried by said bolster and located adjacent to its center. 70
2. In a car truck, a pair of spring supported side frames and a bolster, connections between the ends of said bolster and side frames whereby the latter have free rocking movement for a limited distance in all directions, and a car body supporting spring carried by said bolster. 75
3. In a car truck, a pair of side frames, a bolster bearing directly thereupon, a car body supporting spring carried by said bolster, and rockers interposed between the side frames and a part of the car body. 80
4. In a car truck, a bolster, spring supported side frames connected to the ends thereof and adapted to rock freely for a limited distance in all directions, a body bolster, yielding pressure means interposed between the truck bolster and body bolster, and rockers interposed between the body bolster and side frames. 85
5. In a car truck, a bolster, side frames connected to the ends thereof and adapted to rock freely for a limited distance in all directions, a body bolster, yielding pressure means interposed between the truck bolster and body bolster, rockers interposed between the body bolster and side frames, and portions of the bearing surfaces of said rockers being provided with flat faces which normally engage the side frames. 90
6. In a car truck, a pair of wheel carrying axles, journal boxes for said axles, springs supported by said journal boxes, truck side frames supported by said springs, rocking supports against which the central portions of the side frames engage, a truck bolster, the ends of which bear directly upon said side frames, and a car body supporting spring supported upon the central portion of said bolster. 95
7. In a car truck, a pair of spring supported side frames, a bolster, flexible interlocking connections between the bolster and side frames, a body bolster, and yielding pressure means between the truck bolster and body bolster. 100
8. In a car truck, a pair of spring supported side frames, a bolster, interlocking means between the bolster and side frames, a body bolster, yielding pressure means between the truck bolster and body bolster, and rockers between the body bolster and side frames. 110
9. In a car truck, a pair of wheel carrying axles, side frames yieldingly supported upon 115
10. In a car truck, a pair of side frames, a bolster pivotally connecting the same, a body bolster, yielding pressure means interposed between the truck bolster and body bolster, and rockers interposed between the body bolster and side frames. 120
11. In a car truck, a pair of side frames, a bolster pivotally connecting the same, a body bolster, yielding pressure means interposed between the truck bolster and body bolster, and rockers interposed between the body bolster and side frames. 125
12. In a car truck, a pair of side frames, a bolster pivotally connecting the same, a body bolster, yielding pressure means interposed between the truck bolster and body bolster, and rockers interposed between the body bolster and side frames. 130

It will be readily understood that minor changes in the size, form and construction of the various parts of my improved car truck can be made and substituted for those

said axles, a bolster having its end portions flexibly connected to said side frames, a body bolster pivotally connected to and yieldingly supported above said bolster, and rockers between the side frames and the end portions of said body bolster.

10. In a car truck, a pair of wheel carrying axles, side frames yieldingly supported upon said axles, a bolster having its end portions flexibly connected to said side

frames, a body bolster pivotally connected to and yieldingly supported above said bolster, rockers between the side frames and the end portions of said body bolster, and said rockers being provided with flat surfaces that are adapted to normally engage said side frames. 15

In testimony whereof I hereunto affix my signature this 16th day of July, 1919.

CHARLES T. WESTLAKE.
